UNITED STATES PATENT OFFICE.

JOHN C. WAHL, OF CHICAGO, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

CALCULATING-MACHINE.

1,366,683.

Specification of Letters Patent.

Patented Jan. 25, 1921.

Application filed June 12, 1916. Serial No. 103,216.

To all whom it may concern:

Be it known that I, JOHN C. WAHL, a citizen of the United States, residing at Chicago, in the county of Cook and State 5 of Illinois, have invented a certain new and useful Improvement in Calculating-Machines, of which the following is a specification.

My invention is a calculating machine 10 and is an improvement in or variation on the cross footing machine disclosed in my Patent No. 1,270,471, granted June 25, 1918.

The object of my present invention is to provide a machine adapted to perform horizontal and vertical addition, employing a so-called "jumping" totalizer therefor, and to so arrange this machine that said jumping totalizer may be employed to calculate in a variety of tables.

20 Another object of my invention is to provide a cross footing machine having a single jumping decimal carriage and having means to calculate a plurality of cross footings simultaneously.

25 Another object of my invention is to provide an improved mechanism adapted to perform the above recited operations. These and other objects of my invention will be hereinafter described and claimed.

30 I have provided a typewriter having a Wahl cross-footing calculating mechanism attached thereto. However, the jumping truck, which carries the cross footing totalizer in the structure disclosed in my cited application, instead of having a single totalizer mounted thereon, carries a plurality of totalizers. This truck is held in its normal 35 position by a spring and is picked up by the main carriage of the typewriter at the calculating zones and automatically disconnected therefrom. In the structure shown in my prior patent, the points of pickup and disconnection are invariable throughout a single traverse of the main carriage

40 of the typewriter. This is for the reason that in said structure I have shown but a single totalizer on the cross truck. In the invention disclosed in my present application, I have shown a plurality of totalizers 45 on the cross truck, and in order to calculate in these various totalizers, it becomes necessary to change the point of disconnection of the cross truck from the main truck as said main truck reaches different points of

its travel. I therefore have provided a set 55 of cams on the main truck and these cams through suitable mechanism control the point of disconnection of the cross truck.

A further difference in my herein described invention from the invention shown 60 in my cited patent lies in the fact that in my prior structure, the vertical totalizers themselves carried the connecting locations which served to pick up the cross truck. As will be seen in the description of my present invention, it is not desirable to employ this particular form of pickup in connection 65 with the use of a plurality of totalizers on the cross truck, and I therefore have provided a series of independently locatable 70 pick-ups on the main truck.

My invention may be best understood by reference to the accompanying drawings, of which—

Figure 1 is a front elevation of a calculating machine employing my invention.

Fig. 2 is a section through line 2—2 of Fig. 1, drawn to a greatly enlarged scale.

Fig. 3 is a detail of the connecting locations on the main truck.

Fig. 4 is a perspective view of the means for disconnecting the cross truck corresponding to various positions of the vertical truck.

Fig. 5 is a perspective view of some of the parts shown in Fig. 4 in a changed position.

Fig. 6 is a detail of one of the latches shown in Fig. 4.

Figs. 7, 8, 9, 10, 11 and 12 are diagrammatic views showing the coöperation of the vertical and cross master wheels with their then associated totalizers.

Fig. 13 is a perspective view of the bar having but one connecting location.

Referring to Figs. 1 and 2, 10 represents the frame work of the typewriter on which is mounted a truck 11, which is connected to the printing carriage 12 of the typewriter and progresses step by step therewith. On this truck 11, which I shall hereinafter call the "vertical" truck, are mounted the vertical totalizers 13, 14, 15, 16, 17 and 18. Supported by the framework of the typewriter is the cross truck 19 which is adapted to reciprocate in suitable guides 20 and is held in its normal position by a spring 21, one end 22 of which is fastened to the frame

work 10, and the other end is fastened to the truck 19. The spring 21 is passed around the pulley 23 which is mounted on a stud screw 24 in the frame work 10. On the 5 cross truck 19 are mounted cross totalizers 25, 26 and 27.

The typewriter is provided with a set of numeral keys 28 which are connected by pull rods 29 to the actuating mechanism 30.

- 10 This actuating mechanism is in two parts and serves to rotate a vertical master wheel 31 and a cross master wheel 32 a differential amount according to the particular numeral key 28 depressed. The vertical master wheel 15 31 serves to enter numbers in any of the vertical totalizers 13 to 18 both inclusive, and the cross master wheel 32 serves to enter numbers into any of the cross totalizers 25, 26, and 27. Since the mechanism by which 20 the differential rotation of the master wheels is accomplished is thoroughly described in my cited patent, it is not necessary to describe the same here, since this differential mechanism forms no part of my present invention. The direction of rotation of the 25 vertical master wheel 31 is controlled by the handle 33 and according to the setting of this handle the vertical master wheel may be caused to add, subtract or not rotate at all 30 upon the depression of any of the numeral keys 28.

Correspondingly the direction of rotation of the cross master wheel 32 may be controlled by the setting of the handle 34 which 35 may be set in any of three positions thereby to determine that the cross master wheel 32 shall either add, subtract or not rotate at all upon the depression of any of the numeral keys 28. The cross master wheel 32 may be 40 also under control of the automatic gear shift which is operated by the cams 35, 36 and 37 which are attached to the vertical totalizers 14, 16 and 18, respectively, and serve to operate a roller 38 mounted on an 45 arm on the shaft 39 rotatably mounted in the frame work 10. A handle 40 by its position serves to determine whether the cross master wheel 32 shall be under control of the handle 34 or of the automatic gear shift controlled 50 by the cams 35, 36 and 37. When the handle 40 is in the position shown in Fig. 1, the automatic gear shift is controlled by the cams. When the said handle is shifted to its upper position, the automatic control by 55 the cams 35, 36 and 37 is ineffective and the cross master wheel 32 is controlled by the handle 34. The automatic control for the cross master wheel 32 may be used to determine that said master wheel shall add, subtract or not operate upon the depression of 60 any numeral key 28, this selection being accomplished by either the absence of the cam 35 or by determining the particular distance to which the said cam 35 depresses the 65 roller 38.

In addition to the various gear shifts just mentioned, the machine has a common reversing or error lever 41 which controls both the vertical master wheel 31 or cross master wheel 32 and this error lever when 70 operated serves to throw both of said master wheels into the reverse of their former condition. This is for the purpose of correcting errors.

All these gear shifts have been thoroughly 75 described in my cited patent and it is not necessary in this application to go into the mechanism by which these various functions are accomplished.

I shall now enter upon a description of 80 mechanism which is peculiar to my present invention.

As before noted, the cross truck 19 is adapted to reciprocate in ways 20 and is held in its normal position by a spring 21. 85 Mounted on this truck is a pickup beam 42 (Fig. 4) having thereon a latch 43 which is adapted to be engaged by the connecting stops 44 and 45. I have given numbers to these stops as associated with but one particular group of totalizers. A description of the stops associated with one particular group of totalizers will serve as a description of similar stops associated with the other groups. The stops 44 and 45 are projections 90 on a bar 46 which is adapted to slide in a slot 47 cut in the lower part of the truck 11. The bar 46 has in it a slot 48 which is adapted to engage the lower part of the totalizer side plate 49 and thus the entire bar, and its associated stops 44 and 45, is held in its proper position by the locating of the totalizer of which the plate 49 is a part. Slidably mounted in the pickup beam 42 is a pin 50 which is adapted to slide in a slot 51 in a 100 plate 52 mounted rigid with the frame work. At one end of the slot 51 is a cam surface 53 which engages the pin 50, and thereby disconnects the latch 43 from the particular connecting location or stop on the vertical truck 110 with which said latch may be at that time engaged.

Owing to the fact that there is not one totalizer but a plurality of them on the cross truck, it is necessary to disengage the pickup 115 beam 42 from its connecting location on the vertical truck 11 not at one definite point in the travel of said pickup beam 42, but at a plurality of points in order to bring the totalizers 25, 26 and 27 mounted on the cross 120 truck 19 into their proper relation with the corresponding vertical totalizers 13 to 18 inclusive. Accordingly I have pivoted on the plate 52 at 54, a lever 55 which is held in a normal position against a stop 56 by a 125 spring 57. Said lever is normally in the position shown in Fig. 4, but at certain points in the travel of the main truck 11, may be raised into the position shown in Fig. 5. It is to be noted that when in this 130

position, the cam surface 53 is no longer effective on the pin 50 mounted in the pick-up beam 42, but that a cam surface 58 on the lever 55 will intercept the pin 50 before the same reaches the cam surface 53 and by its action disconnect the latch 43 from the connecting locations 44 or 45 with which it may then be engaged and the cross truck 19 will accordingly be drawn back by the 10 spring 21 to its normal position. In addition to the lever 55, I have shown a second lever 59 having a cam surface 60 held in its normal position by the spring 61 against the stop pin 62, and it will be evident from inspection of Fig. 5 that if the lever 59 is raised into the position shown in said figure before the pin 50 passes said lever, that both the cam surface 53 and the cam surface 58 will be ineffective to disconnect the pickup 15 beam from the vertical truck, for the cam surface 60 by contact with the pin 50 will cause this disconnection.

I shall now describe the means by which the levers 55 and 59 are operated. Rotatably mounted on the shaft 39 is a lever 64 having mounted on the end 65 thereof a roller 66, and pivoted on the end 67 thereof a link 68. The link 68 has mounted in its end a pin 69 which is guided in a slot 70 in the plate 25 52. Mounted in the link 68 is a pin 71 which is adapted to contact with an arm 72 of the lever 55, and thereby rotate said lever about its pivot 54. Similarly a second pin 73 contacts with an arm 74 on the lever 30 59, which is pivoted on the plate 52 at 75, and rotates said lever 59 about its pivot 75. The position of the levers 55 and 59 is determined by the presence or absence of a cam 35 76 on any of the vertical totalizers 13 to 18 inclusive. The cam 76 has a nose 77 which is adapted to contact with and depress the roller 66 when the totalizer on which said cam is mounted is in its units position. Said nose 77 is long enough to hold said roller 66 40 depressed while the cross-footing totalizer jumps to its sub-units position. From what has gone before it is apparent that depression of the roller 66 will result in the throwing of the levers 55 and 59 into the 45 position shown in Fig. 5, and in case the pin 50 50 happens to be in the position shown in either of the positions 50' or 50'', said pin will be immediately acted on by either the cam surface 58 or the cam surface 60. We 55 thus can formulate the general rule that in the absence of the cam 76, the pickup beam 42 will be disconnected from the vertical truck when the pin 50 reaches the cam surface 53. The presence of the cam 76, how- 60 ever, will serve to disconnect the pin either by the cam surface 58 or the cam surface 60 and which one of these cam surfaces will be effectual is determined by the position of the connecting locations 44 and 45.

65 Mounted on the plate 52 is an auxiliary

plate 78, which is held to the plate 52 by screws 79 and 80, these screws engaging, the one any one of a series of holes 81, and the other any one of a series of holes 82, a plurality of holes being provided in the plate 70 52 in order to permit of the adjustment of the auxiliary plate 78 to take care of variations in the sizes of the totalizers which may be used on the cross truck 19. On the auxiliary plate 78 is pivoted at 83 a latch 84 held 75 by a spring 85 in a normal position. This position is determined by having a stud 86 rigidly mounted in the latch 84 and to which the spring 85 is attached projecting through said latch into the slot 87 in the auxiliary 80 plate 78. The function of the latch 84 is to supplement the tension of the spring 88, Fig. 4, which serves to hold the pickup beam 42 in a position to engage any of the connecting locations 44, 45, etc. When the cross 85 truck is at rest in its normal position, the typewriter carriage and its connecting locations may be tabulated to the left. The connecting locations will then engage the latch 43 with somewhat of a jar and it is advisable 90 to have an extra spring tension to prevent the disengaging of said latch from the connecting locations. On the other hand, when the latch 43 is disconnected from the connecting locations by reason of contact of the 95 pin 50 with any of the cam surfaces 53, 58 and 60, it is desirable that the force holding the latch 43 into the connecting locations be small. It will be observed that the upper 100 surface of the lever 84 forms a continuation of the lower surface of the long slot 89 in the plate 52. This is for the purpose of preventing the accidental disengagement of the latch 43 from any of the connecting locations, said slot 89 having a width approximately equal to the diameter of the 105 pin 50. The lower portion of the slot 89 has a recess 90 opposite the lever 84, also a recess 91 opposite the lever 59, and a recess 92 opposite the lever 55.

110 It will be observed that when the two levers 55 and 59 are in their normal positions, as shown in Fig. 4, the upper sides of these levers form a continuation of the lower line of the slot 89. However, when these levers are raised so as to cause the disconnection of the pin 50 as shown in Fig. 5, then the recess 91 and the recess 92 are uncovered, and it is possible for the cam surfaces associated with said levers 55 and 59 115 to act effectually on the pin 50 and thereby disconnect the pickup beam 42 from its then engaged connecting location.

120 Referring to Fig. 3, the bar 46, shown therein, has two connecting locations 44 and 45, rigid with said bar. This arrangement is not necessary in all cases, but depends upon the arrangement and capacities of the totalizers 25, 26 and 27 on the cross truck. In Figs. 7 and 13, I have shown an alterna- 125 130

tive construction in which the bar 93 has a single connecting location 94 mounted thereon and has a plurality of slots 95, 96, 97 and 98 in the bar 93, these slots being adapted to receive the heel 49 of any of the vertical totalizers. The slots 95, 96, 97 and 98 are placed $\frac{1}{16}$ of an inch apart, this distance being the usual pitch of the totalizer, and therefore the connecting location 94 may be located at any desired point on the vertical truck 11.

I shall now describe a concrete illustration of a form of account which may be handled on my improved machine and in explanation thereof, refer to Figs. 7 to 12, inclusive, which show the various arrangements of the vertical and cross totalizers when engaged with their respective master wheels.

In Fig. 7, the connecting locations are so arranged that the vertical master wheel 31 is entering numbers into the vertical totalizer 13 and the cross master wheel 32 into the cross totalizer 25. When the units place of the totalizer 13 has been reached the pickup beam is disconnected from the connecting location 44 and is connected to the succeeding location 45. When in this position the vertical master wheel 31 is entering numbers into the vertical totalizer 14 and the cross master wheel 32 is subtracting numbers from the cross totalizer 25. This arrangement is shown in Fig. 8.

Coming now to the next group of vertical totalizers, Fig. 9 shows the vertical master wheel 31 entering numbers in the vertical totalizer 15 and the cross master wheel 32 simultaneously entering numbers into the cross totalizer 26, the connecting location in this case being the side plate of the vertical totalizer 16. After the number has been entered into the vertical totalizer 15 and the cross totalizer 26, the pickup beam is disconnected and the mechanism assumes the position shown in Fig. 10. In this figure the numbers are being entered into the vertical totalizer 16 and subtracted from the cross totalizer 26. The vertical truck is then moved to the left and the vertical master wheel 31 comes into engagement with the vertical totalizer 17 and the cross master wheel 32 into engagement with the cross totalizer 27, heels on the side plates of the vertical totalizers 17 and 18 being used for the connecting locations, as is shown in my cited patent. The vertical truck passes on to the next location and the vertical master wheel engages the totalizer 18 and the cross master wheel the cross totalizer 27. Since the relation of the cross truck 19 to the vertical totalizers 17 and 18 when performing the calculation shown in Figs. 11 and 12 is the same as when the machine is in its normal position, it is not

necessary to provide any additional connecting locations for these two positions, the heels on the right side plates of the totalizers 17 and 18 serving to pick up the pickup beam.

It is obvious by the arrangement herein shown that the cross totalizers 25, 26 and 27 need not calculate in the same tables. For instance, I can have the vertical group 13 and 14 calculate in weights, the vertical group 15 and 16 calculate in English money and the vertical group 17 and 18 calculate in American money. Correspondingly, the cross totalizer 25 would calculate in weights, the cross totalizer 26 would calculate in English money, and the cross totalizer 27 would calculate in American money. While in the arrangement given I have shown the vertical totalizers in two groups and a single cross totalizer co-operating with each of these groups, this precise arrangement is by no means necessary, since by reason of being able to change both the point of connection as determined by the position of the connecting locations 44 and 45 and the point of disconnection as determined by the action of the cams 53, 58 and 60, I am enabled to get a great variety of different arrangements and combinations between the vertical and cross totalizers. It is not necessary in this place to give an extended list of these combinations, since they will be apparent to those skilled in the art.

While I have shown each cross totalizer calculating with the group of vertical totalizers which are placed adjacent to each other, *e. g.*, the cross totalizer 25 serving to calculate numbers entered into the vertical totalizers 13 and 14, the cross totalizer 26 serving to cross foot numbers entered into the vertical totalizers 15 and 16, etc., it is evident that this arrangement is not necessary and that any one of the cross totalizers may calculate numbers written in columns which are not adjacent to each other. A set-up of the machine to accomplish this can evidently be made by re-adjusting the connecting locations 44 and 45, and also by providing suitable cams 76 on the totalizer to change the disconnecting point. It is also true that the number of totalizers in a vertical group is not limited to two, since there may be more than two; in fact, the only limit to the number of vertical totalizers which will calculate in the main totalizer on the cross truck is the available space on the vertical truck.

I also wish to call attention to the fact that the lever 64 in my present application, in addition to governing the levers 55 and 59 has also the same function as the lever numbered 478 in my cited patent. Reference thereto will disclose that said lever 478 controls an interlock between the jumping to-

talizer and the vertical truck, the object of this interlock being to lock up the entire calculating machine in case the cross totalizer should accidentally become disconnected from its connecting location. In my present application, the lever 64 has three positions. There is one position in which it is not affected by any cam. There is a second position in which it rests on the surface 10 of the cam 76, and there is a third position in which it contacts with the nose 77 of the cam 76. In the first of these positions, the calculating machine is unlocked. In the second, the calculating machine is locked 15 except when the cross truck is picked up and displaced from its normal position. In the third of these positions the lock referred to still persists, but in addition, the levers 55 and 59 are displaced into the position shown 20 in Fig. 5.

In some of the claims I have used the expression "totalizers calculating in two different tables." For the sake of brevity, I have used this term to denote also totalizers 25 which calculate in the same table, but have a different spacing relative to the number wheels. For instance, I wish to be understood that I consider a totalizer spacing $999 \times 999 \times 99$ and a totalizer spacing 30 999999×99 as the mechanical equivalents of two totalizers computing in different tables for the reason that it is just as impossible to use a totalizer spacing $999 \times 999 \times 99$ as a vertical totalizer with a totalizer spacing 35 999999×99 as a cross totalizer, as it is to use a totalizer calculating in one table as a vertical totalizer and a totalizer calculating in a different table as a cross totalizer.

For the sake of brevity in the claims I 40 have used the term "totalizers calculating in two tables" to denote either totalizers which compute in two different tables, such for instance, as a totalizer computing in American money which is to the base 10, and a totalizer 45 computing in English money, which is to the bases 10, 20 and 12, or totalizers computing in the same table but having their actuating wheels arranged in different spacings. It is obvious that even if two totalizers 50 computed in the same table but had their number wheels arranged in different spaces, it would be impossible to use them simultaneously as a vertical and cross totalizer.

I believe I am the first to disclose the plan 55 by which a machine having a single jumping decimal carriage can cross foot in a variety of tables simultaneously. There have been machines proposed which, while having but a single jumping carriage, could compute in different tables during a single run of the main carriage, but in these machines it was necessary to first clear the cross totalizer of the amount computed in one

table before entering the amount to be computed in a second table. Obviously with my machine, a number in one table may be accumulated in the totalizer 25 and without clearing said totalizer, a number in a different table may be accumulated in a totalizer 26. After all the accumulation has been done these totalizers may then be separately cleared so that the single jumping truck may be said to permit the simultaneous cross computation of the amounts in 75 the different tables. I believe this arrangement is new with me and I wish to claim the same broadly.

Many changes and variations may be made in the precise structure herein described since I claim:

1. In a calculating machine, the combination of a frame work, a decimal carriage movable relative thereto, a second decimal carriage also movable relative to said frame 85 work, means to cause said carriages to move in synchronous relation, mechanism to disconnect said carriages when said second carriage has reached a certain position relative to said frame work, and other mechanism 90 to disconnect said second carriage when said carriage has reached a second position relative to said frame work.

2. In a calculating machine, the combination of a frame work, a decimal carriage 95 movable relative thereto, a second decimal carriage also movable relative to said frame work, means to cause said carriages to move in synchronous relation, means to disconnect said carriages when said second carriage 100 has reached a certain position relative to said frame work, other means to disconnect said second carriage when said carriage has reached a second position relative to said frame work, and means to determine 105 which of said disconnecting means shall be effective.

3. In a calculating machine, the combination of a frame work, a decimal carriage 110 movable thereto, a second decimal carriage also movable relative to said frame work, means to cause said carriages to move in synchronous relation, means to disconnect said carriages when said second carriage has reached a certain position relative to said 115 frame work, other means to disconnect said second carriage when said carriage has reached a second position relative to said frame work, and means controlled by said first carriage to determine the point of disconnection of said second carriage.

4. In a calculating machine, the combination of a frame work, a decimal carriage 125 movable relative thereto, a second decimal carriage, also movable relative to said frame work, means to cause said carriages to move in synchronous relation, means to disconnect said carriages when said second carriage has

- reached a certain position relative to said frame work, other means to disconnect said second carriage when said carriage has reached a second position relative to said frame work, and means controlled by said first carriage to determine which of said disconnecting means shall be effective. 5
5. In a calculating machine, the combination of a frame work, a decimal carriage movable relative thereto, a second decimal carriage also movable relative to said frame work, means to cause said carriages to move in synchronous relation, means to disconnect said carriages when said second carriage has reached a certain position relative to said frame work, other means to disconnect said second carriage when said carriage has reached a second position relative to said frame work, and a cam device controlled by said first carriage to determine which of said disconnecting means shall be effective on said carriage. 10
6. In a calculating machine, the combination of a frame work, a decimal carriage movable relative thereto, a second decimal carriage also movable relative to said frame work, means to cause said carriages to move in synchronous relation, means to disconnect said carriages when said second carriage has reached a certain position relative to said frame work, other means to disconnect said second carriage when said carriage has reached a second position relative to said frame work, and a cam device mounted on said first carriage to determine which of said disconnecting means shall be effective on said carriage. 15
7. In a calculating machine, the combination of a frame work, a decimal carriage movable relative thereto, a second decimal carriage also movable relative to said frame work, means to cause said carriages to move in synchronous relation, means to disconnect said carriages when said second carriage has reached a certain position relative to said frame work, other means to disconnect said second carriage when said carriage has reached a second position relative to said frame work, and a cam and follower device controlled by said first carriage to determine which of said disconnecting means shall be effective. 20
8. In a calculating machine, the combination of a frame work, a decimal carriage movable relatively thereto, a second decimal carriage also movable relative to said frame work, means to cause said carriages to move in synchronous relation, means mounted on said frame work to disconnect said carriages when said second carriage has reached a certain position relative to said frame work, a lever mounted on said frame work and adapted when in a displaced position to disconnect said second carriage, and automatic means to control the position of said lever. 25
9. In a calculating machine, the combination of a frame work, a decimal carriage movable relatively thereto, a second decimal carriage also movable relative to said frame work, means to cause said carriages to move in synchronous relation, means mounted on said frame work to disconnect said carriages when said second carriage has reached a certain position relative to said frame work, a lever mounted on said frame work and adapted when in a displaced position to disconnect said second carriage, and means under control of said first decimal carriage to determine the position of said lever. 30
10. In a calculating machine, the combination of a frame work, a decimal carriage movable relatively thereto, a second decimal carriage also movable relative to said frame work, means to cause said carriages to move in synchronous relation, means mounted on said frame work to disconnect said carriages when said second carriage has reached a certain position relative to said frame work, a lever mounted on said frame work and adapted when in a displaced position to disconnect said second carriage, and a cam and follower device to control the position of said lever. 35
11. In a calculating machine, the combination of a frame work, a decimal carriage movable relatively thereto, a second decimal carriage also movable relative to said frame work, means to cause said carriages to move in synchronous relation, means mounted on said frame work to disconnect said carriages when said second carriage has reached a certain position relative to said frame work, a lever mounted on said frame work and adapted when in a displaced position to disconnect said second carriage, and a cam and follower device controlled by said first carriage to control the position of said lever. 40
12. In a calculating machine, the combination of a frame work, a decimal carriage movable relatively thereto, a second decimal carriage also movable relative to said frame work, a series of connecting locations on said first decimal carriage, a latch connected to said second decimal carriage, means to cause said latch to engage said connecting locations, mechanism to disconnect latch from said connecting locations when said second decimal carriage has reached a predetermined point relative to said frame work, and other mechanism to disconnect said latch from said connecting locations when said second carriage has reached a second predetermined point relative to said frame work. 45
13. In a calculating machine, the combination of a traveling member, a decimal carriage, means to connect intermittently said decimal carriage, to said traveling member during a single traverse thereof, a plurality

- of totalizers coöperating with said decimal carriage, a master mechanism adapted to coöperate with any of said totalizers, and means to carry on simultaneous cross computations in said totalizers during a single traverse of said traveling member. 65
14. In a calculating machine, the combination of a traveling member, a decimal carriage; means to connect intermittently 70
10 said decimal carriage to said traveling member during a single traverse thereof, a master mechanism and two totalizers removably and slidably mounted on said decimal carriage said totalizers being adapted to 75
15 have numbers inserted therein by said master mechanism whereby simultaneous cross computations may be carried on in said totalizers during a single traverse of said traveling member.
16. In a calculating machine, the combination of a traveling member, a jumping decimal carriage adapted to be connected intermittently to said traveling member, a shiftable disconnecting means to determine the 80
20 point of disconnection of said jumping carriage from said traveling member, and means to determine the position of said disconnecting means. 85
17. In a calculating machine, the combination of a traveling member, a jumping decimal carriage adapted to be connected to said traveling member, a shiftable disconnecting means to determine the point of disconnection of said jumping carriage from said traveling member, and a cam device 90
30 to determine the position of said disconnecting means. 95
18. In a calculating machine, the combination of a traveling member, a jumping decimal carriage, two totalizers adapted to compute in different tables associated with 100
40 said decimal carriage, a master mechanism adapted to coöperate with either of said totalizers, means to cause intermittent connection and disconnection of said decimal carriage with said traveling member, and totalizer actuating means, the arrangement of the totalizers, totalizer actuating means, and intermittent connecting means being 105
45 such that simultaneous cross computations of quantities in different tables may be carried on in said totalizers. 110
19. In a calculating machine, the combination of a traveling member, a jumping 115
50 truck adapted to be intermittently connected to said traveling member, two totalizers removably mounted on said jumping truck, and means to permit computations in either of said totalizers at will. 120
20. In a calculating machine, the combination of a traveling member, a jumping truck adapted to be intermittently connected to said traveling member, two totalizers removably mounted on said jumping truck, and means under control of said traveling member to determine in which of said totalizers computations shall be made. 125
21. In a calculating machine, the combination of a traveling member, a jumping truck adapted to be intermittently connected to said traveling member, two totalizers removably mounted on said jumping truck and means mounted on said traveling member to determine in which of said totalizers computations shall be made. 130
22. In a calculating machine, the combination of a traveling member, a series of adjustable connecting locations mounted on said traveling member, a totalizer mounted on said traveling member, and connections 90
50 between said totalizer and said connecting locations to hold the same in a fixed position relative to each other. 135
23. In a calculating machine, the combination of a traveling member, a bar having 95
55 connecting locations mounted thereon and a series of slots cut therein, means to support said bar in said traveling member, and a totalizer, part of which is adapted to engage said slots and thereby hold said bar in 100
60 a definite position on said traveling member. 140
24. In a calculating machine, the combination of a traveling member, a bar having a connecting location mounted thereon, and a series of slots cut therein, means to support said bar on said traveling member, and a totalizer adjustable on said traveling member, part of said totalizer being adapted to engage one slot and thereby hold said bar in 105
65 a definite position on said traveling member. 145
25. In a calculating machine, the combination of a traveling member, a connecting location mounted thereon, a totalizer mounted thereon, and an adjustment between said totalizer and said connecting location 110
70 whereby the latter may be displaced relative to the first. 150
26. In a calculating machine, the combination of totalizer actuating mechanism, a series of vertical totalizers adapted to compute in different tables, a traveling member serving as a support for said totalizers, a truck adapted to be intermittently connected to said traveling member, a plurality of cross totalizers of different tables mounted on said truck, and means to bring said vertical and cross totalizers into the proper decimal relation so that when a number is entered by 155
75 125

said actuating mechanism into a vertical totalizer computing in one table, the same number shall be simultaneously entered into the cross totalizer computing in the same 5 table.

27. In a calculating machine, the combination of a traveling member, a decimal carriage adapted to be intermittently connected to and disconnected from said traveling 10 member, a set of numeral keys, a lock for said numeral keys, shiftable means to vary the point of disconnection of said jumping decimal carriage from said traveling member, and a single lever jointly controlling 15 said lock and said shiftable disconnecting means.

28. In a calculating machine, the combination of a traveling member, a decimal carriage adapted to be intermittently connected 20 to and disconnected from said traveling member, a set of numeral keys, a lock for said numeral keys, shiftable means to vary the point of disconnection of said jumping carriage from said traveling member, and a 25 lever controlled by said member to operate said lock and shiftable means.

29. In a calculating machine, the combination of a traveling member, a decimal carriage adapted to be intermittently connected 30 to and disconnected from said traveling member, a set of numeral keys, a lock for said numeral keys, shiftable means to vary the point of disconnection of said jumping carriage from said traveling member, and a 35 lever controlled by the cam on said traveling

member to control jointly said lock and said shiftable means.

30. In a calculating machine, the combination of a traveling member, a jumping decimal carriage adapted to be connected intermittently to said traveling member, a shiftable disconnecting means to determine the point of disconnection of said jumping carriage from said traveling member and means under control of said traveling member to 40 determine the position of said disconnecting means.

31. In a calculating machine, the combination of a traveling member, a series of adjustable connecting lugs slidably mounted on 45 said traveling member, a totalizer mounted on said traveling member, and connections between said totalizer and said connecting lugs to hold the same in a fixed position relative to each other, whereby the adjusting of 50 said totalizer relative to said traveling member will simultaneously adjust the attached connecting lugs.

32. In a calculating machine, the combination of a traveling member, a groove in said 55 traveling member, a connecting lug mounted in said groove, a totalizer mounted on said traveling member, and an adjustment between said totalizer and said connecting lug whereby the latter may be displaced relative 60 to the first and held by the totalizer in its displaced position.

In witness whereof, I have hereunto signed my name this ninth day of June, 1916.

JOHN C. WAHL
